UNITED STATES PATENT OFFICE.

HENRY ROHWER, OF SEATTLE, WASHINGTON.

MONEY-VALUE INDICATOR.

1,376,832.

Specification of Letters Patent. Patented May 3, 1921.

Application filed April 26, 1917. Serial No. 164,606.

To all whom it may concern:

Be it known that I, HENRY ROHWER, a citizen of the United States, and a resident of Seattle, county of King, State of Washington, have invented certain new and useful Improvements in Money-Value Indicators, of which the following is a specification.

My invention relates to machines for use 10 in making up pay-rolls, or other similar uses. It is particularly useful in ascertaining the number of coins or bills to be drawn from the bank in preparation for the payment of a number of employees drawing different wages.

The object of my invention is to devise a machine of the nature generally described above, which will be mechanically simple and of sufficient mechanical strength to 20 stand the wear incident to such machine.

In making up pay-rolls for a large number of employees, drawing wages of odd dollars and cents, it is a difficult problem to ascertain the exact number of the different 25 denominations of money values required to make these payments and at the same time have the exact change for each one.

By the use of my invention as embodied in the following description of the attached 30 drawings, this difficulty is wholly overcome and after the machine has been operated, as hereinafter explained, in accordance with the figures representing the wages of each individual, the total number of the different 35 denominations of money appears upon the face of the machine in accessible form.

The accompanying drawings, forming a part of the specification, illustrate one embodiment of my invention in the form of a 40 machine which I have constructed and operated.

In the drawings, Figure 1 shows a front plan view with one of the dials shown partially in section;

Fig. 2 shows a section of the machine 45 through line 2-2 of Fig. 1, with the casting applied;

Fig. 3 shows a rear plan view of the 50 denomination dials with the contacts arranged thereon;

Fig. 4 shows a schematic wiring diagram of the machine;

Fig. 5 shows an enlarged detail of one of the indicators partly in section;

Fig. 6 shows a section on the line 6-6

of Fig. 5, the same being a more detail showing of part of the indicator;

Fig. 7 shows a detail of one of the indicator wheels, as shown in Figs. 5 and 6;

Fig. 8 shows the clutch for connecting the 60 motor with the indicator operating shaft;

Fig. 9 shows a section through the line 9-9 of Fig. 8;

Fig. 10 shows an enlarged sectional view 65 of one of the operating magnets for selecting the indicators;

Fig. 11 shows a modification of the arrangement of contacts on the cents denomination dial;

Fig. 12 shows a detail of one of the 70 indicator operating arms; and

Fig. 13 shows a fragmentary front view with the numbers appearing as the machine is set.

Referring to the drawings, I will describe 75 in detail the machine represented thereby, merely to show one embodiment of the invention, and it is, of course, understood that my invention is not limited to the machine as shown in the drawings. The machine as 80 shown embodies a shaft 1 having mounted thereon the indicators 2 to 11. Each of these indicators has a plurality of wheels 12, 13 and 14, (Fig. 5) representing units, tens and hundreds. These numbers are, of course, 85 visible through a suitable opening in the front of the casing 146. The motor operated shaft 15 has a plurality of arms 16 to 31. Some of these arms are single, as shown in Fig. 2, and others are double, as shown 90 in Fig. 12.

Mounted on the shaft 1, with the indicators, are a number of arms 32 to 47, inclusive. Each of these arms is arranged so that when the shaft 15 is revolved, at least 95 one of the arms 16 to 31 will come in contact with each one of the arms 32 to 47. Each of the arms 32 to 47 is loosely mounted on the shaft 1, and each of these arms 32 to 47 has a spring 48 attached thereto and normally holding the arm in the position shown by the arm 40 in Fig. 2. The arms 16 to 31 are mounted on the shaft 15 at an angle to each other so as to make the load on the motor more uniform, but since the motor 105 operates through a speed reduction worm, it is evident that the arms 16 to 31 may be placed at any desired angle with respect to each other.

By reference to Fig. 2, it will be seen that 110

the arm 40 has a shoulder 49 on the underside thereof. There is a dog 50 mounted on the shaft 1 so as to move concentrically with the arm 40 and the indicator wheels. 5 This arrangement is shown more in detail in Fig. 6. Each of the arms 32 to 47 has a dog 50 arranged in the same manner as shown in Fig. 2 and a description of one will be sufficient for all.

10 In Fig. 2 is shown an electro-magnet 51. This magnet, when energized, moves a push-arm 52 against the dog 50, thereby throwing the same in behind the shoulder 49 on the arm 40. This push-arm has a shoulder 15 53 thereon. There is a dog 54 mounted on the shaft 55 and held against the push-arm by spring 56. When the magnet moves the push-arm so as to throw the dog 50 in behind the shoulder 49 on the arm 40, the dog 20 54 likewise moves in behind the shoulder 53 on the push-arm and holds the push-arm in against the tension of the compression spring 57 so as to keep the dog 50 in engagement with the shoulder 49. The dogs 25 54 are loosely mounted on the shaft 55, but each one has a radial groove 135 in the hub thereof. (See Fig. 10.) Through this groove extends a pin 136 fastened in the shaft 55. The groove is wider than the pin so 30 that a certain amount of lost motion exists between the dog 54 and the shaft 55. Mounted so as to move concentrically with the indicator wheel is an actuating pawl 58 for the unit wheel indicator. This pawl is mounted 35 so as to move concentrically with the wheel and is arranged to move the wheel forward one step each time it is actuated. Attached to the mounting of the dog 58 is a coil spring 116 which acts to return it to its 40 initial position. The above features of the indicator are old and form no part of the present invention and therefore further detail description is unnecessary.

From the foregoing it will be seen that 45 the movement of the arm 40 will cause the counter wheel to move forward one step provided the push-arm 52 has thrown the dog 50 into position. The electro-magnets are selectively operated by means of certain 50 electrical connections which are set up through the instrumentality of the dials shown in Fig. 3 and will be described in detail hereinafter.

From an inspection of Fig. 4 showing the 55 electrical circuits in diagram, it will be seen that there are sixteen electro-magnets 51, 117—131, inclusive. All of these magnets and their mechanical arrangement are identical and therefore a description of one is 60 sufficient. These magnets are all connected to the common wire 59. There is a wire leading from each magnet to a contact 60, 61, 62, 63, 64, 65, 66, 67, 68, 69, 70, 71, 72, 73, 74 and 75. There are also two common contacts 76 and 77 connected together by wire

78 leading to the other side of the supply line. All of the contacts 60 to 77 are mounted on a piece of insulating material 79 shown in Figs. 1 and 2. This contact bar 79 is loosely mounted so that it is moved 70 up and down by the arm 80 when operated by the button and rod 81 (Fig. 2). The contacts mounted on the bar 79 are of the type such that the contacting portion is resiliently mounted so as to account for any 75 irregularities in the contacting surfaces.

Each of the dials 140 and 141 has on its face, and near its circumference, a series of numbers from 1 to 100. As indicated in Fig. 1, the numbers on the cents dial are 80 numbered from 1 to 100 consecutively in a counterclockwise direction beginning at the bottom, whereas the dollar wheel is numbered from 1 to 100 consecutively counterclockwise, beginning at the top. Each of 85 the dials has on its circumference a series of notches. These notches are spaced a distance equal to the distance between the numbers on the face of the dial. Arranged to engage in these notches is a dog 143 on the cents dial and 142 on the dollar dial, these 90 dogs being actuated by coil springs 144, as shown in Fig. 1. These dogs make it easy to get the correct position of the desired number which appears beneath a glass which 95 covers an opening 145 in the casing 146, as shown in Fig. 13. They also hold the dials in position while the contacts are being made. It is understood that in the movement of the dials by the handles 138 and 100 139, they are usually moved to the right, but since the numbers are read on the right-hand side of the center of the dollar-wheel and the left-hand side of the center of the cents wheel, the arrangement of the numbers 105 on the circumference, as well as the contacts, underneath will be made in accordance with the arrangement above specified. It is, of course, evident that the wheels may be readily turned to the left, and frequently 110 are, when in moving them one way, the number desired is overrun. The pawls 142 and 143 permit the movement of the wheel as well in one direction as in the other.

In Fig. 3 are shown the denomination 115 dials 140 and 141. The dial on the left of the figure represents values below a dollar and is called the cents dial, and the dial on the right represents values above a dollar, and is called the dollars dial. Each of these 120 dials has a plurality of rows of contacts all arranged concentrically. Each row or circle of contacts represents one denomination of cents or dollars as the case may be. For instance, on the cents dial, Fig. 3, the ring 125 76 designates a common contact connected to one side of the line. The circle of contacts designated at 67 represents the 50¢ denomination. The one designated at 66 represents the 25¢ denomination. The one 130

designated at 65 represents one 10¢ denomination. The one designated at 64, designates another 10¢ denomination, and the one designated at 63, represents the 5¢ denomination. 62 represents two 1¢ denominations and 61 represents two 1¢ denominations, and 60 represents the single 1¢ denomination. Likewise, in the dollar dial, 77 represents the common contact. 75 represents \$40; 74 likewise represents \$40; 73 represents \$20; 72 represents \$10; 71 represents \$5; 70 represents \$2; 69 represents \$2 and 68 represents \$1. Each circle of contacts is arranged to remain at all times above one of the corresponding contacts shown in Fig. 4. The contacts are so arranged in each of the rows that they engage the corresponding contact on the contact bar 79 only at certain predetermined times or positions. For instance, as the dials are shown in Fig. 3, the contacts on the bar 79 will engage the contacts 77, 74, 73, 72, 71 and 68, which contacts, respectively, represent common, \$40, \$20, \$10, \$5, \$1, making a total of \$76.

On the cents wheel, the contacts on the bar 79 engage 76, 67, 66 and 60, representing respectively common, 50¢, 25¢ and 1¢, making a total of 76¢. It will be seen from this that the contact rows 75, 70 and 69 on the dollar dial are not in engagement with the corresponding contacts on the bar 79, and that the rows or circles of contacts 61, 62, 63, 64 and 65 are not in engagement with the corresponding contact on the bar 79. It is the position of the various contacts in these rows or circles which make the different combinations possible in the different positions of the cents and dollar dials. It is understood, of course, that all of the contacts in a given row, as well as all of the rows of contacts are united electrically in that they are all connected with the common contact 76 on the cents wheel and 77 on the dollar wheel. As a matter of fact, the wheels might be made in any suitable form to give the combinations required. The arrangement of the contacts, both as to the number of rows, as well as the particular location of the contacts in the individual rows may be changed dependent upon the results desired. For instance, the arrangement as shown in Fig. 11 at the position "X" could be substituted for the arrangement at "X" on the cents dial of Fig. 3, in that instead of having the contact 66 represent the 25¢ piece, single contacts, as in Fig. 11, might be provided in the rows 65, 64 and 63, so that instead of indicating one 25¢ piece, the contacts will indicate two dimes and a nickel. Likewise, at the point "Y" in Fig. 3, the contact on the row 67 could be eliminated and contacts placed in the rows 66, 65, 64 and 63, as shown at "Y" in Fig. 11, this giving, instead of a 50¢ piece, as in Fig. 3, a 25¢ piece, two dimes

and a nickel. Likewise, in the position "Z," Fig. 3, the contact in the row 66 could be removed, and instead thereof, contacts placed in the rows 65, 64 and 63, as in the positions shown in Fig. 11, thus instead of representing a 50¢ and a 25¢ piece, a 50¢ piece, two dimes and a nickel would be represented.

I have shown a circular dial merely as illustrating the principle of my invention, but it is evident that as long as the denomination contacts are brought so as to engage the corresponding magnet contacts on the bar 79, it is immaterial whether I use a dial or some other equivalent means of bringing about this selective combination.

The electro-magnet shown in Fig. 10, has a U-shaped iron frame 82, in which is rigidly held an armature 83. The armature 83 has an opening therethrough, through which passes a rod 84. On the opposite end of the rod 84 is a movable armature 85 into which the rod 83 is threaded. When the magnet is energized the armature 85 moves to the left and carries with it the rod 84 to which is attached the member 86 which is suitably connected to the push-rod 52, and actuates the same to set the dog 50 in operative position. The rod 84 has a lock-nut 87 on the screw-threaded end thereof so that the length of stroke of the rod may be varied or adjusted from time to time as the case may require.

In Fig. 7, I have shown an enlarged detail of one of the indicator wheels. All of the indicator wheels are identical, and therefore a description of one will suffice for all. Each wheel has a radial groove formed in the side, as shown at 88, in Figs. 5 and 7. There is also a circular groove 89 formed in the side of the wheel and in the groove 89 is placed a band spring 90 with one end fastened into the side of the wheel. In the groove 88 is placed a pin 91, one end of which is engaged by the spring 90 and the other end of which engages the shaft 1 which has a longitudinal inset 92, whereby a shoulder 93 is formed on the shaft.

From the foregoing, it will be evident that the wheel may be moved on the shaft freely in the direction of the arrow, as shown in Fig. 7, but the same cannot be given a complete revolution in the opposite direction by reason of the fact that the pin 91 will engage with the shoulder 93. The prime object of this construction is to form a ready means of placing all of the indicator wheels back to zero by revolving the shaft 1 in a counterclockwise direction (as shown in Fig. 7) by means of the handle 94, as shown in Fig. 1.

In Fig. 2 is shown a motor 95 having a shaft 96 with a worm 97 thereon. This shaft is suitably journaled as at 98. The worm 97 engages a worm wheel 99 loosely mounted on the shaft 15. This arrange-

ment is shown in detail in Fig. 8. Rigidly mounted to the shaft 15 is a collar 100 having pins 101 placed longitudinally therein. The worm-wheel 99 likewise has pins 102 placed longitudinally therein. There is a collar 103 loosely mounted on the shaft 15. This collar 103 has four cam grooves 104 placed 90° apart on the side thereof and arranged to engage at certain times with the 10 ends of the pins 102 in the worm wheel. On the other side of the collar 103 are provided two holes into which the pins 101 loosely fit. Therefore, the collar 103 is arranged so as to be freely slidable on the 15 shaft 15 and pins 101. Mounted under compression and around the shaft 15 and beneath the collars 100 and 103 is a coiled spring 105. On the collar 103 is a radial pin 106, shown in dotted lines in Figs. 8 20 and 9. This pin 106 engages an arm 107 which is constantly held in contact with the collar 103 by means of the spring 108. This arm 107 has a cam surface 109 on one side of the end thereof which engages the pin 25 106, as shown in Fig. 8, to move the collar 103 out of contact with the pins 102 on the worm wheel. When it is desired for the collar 103 to engage the pins 102, or, in other words, when a selective combination 30 has been set up by the dials, the button 81 is pressed, which operates the lever 80 to which is attached an arm 110, as shown in Fig. 2. Pivoted to the arm 110 is an arm 111, which arm 111 is fulcrumed at 112 in 35 the standard 113, as shown in Fig. 9. When the arm 110 is pressed downwardly, the arm 107 is moved to the right, as shown in Fig. 9, so that it clears the end of the pin 106, thereby permitting the spring 105 to 40 throw the collar 103 to the right, as shown in Fig. 8, so that it will engage the pins 102 mounted in the worm wheel, thereby causing shaft 15 to revolve with the worm wheel 99. The arms 107 and 111 are connected so 45 that they move together.

As shown in Fig. 12, some of the arms mounted on the shaft 15 are bifurcated, or having two engaging portions 114 and 115. The arms 17, 18, 25, 26, 30 and 31 are double arms, such as that shown in Fig. 12. This type of arm is used when it is desired to count up or indicate two of a given denomination, such, for instance, as two pennies as in the case of the arms 17 and 18; or 50 two one dollars as in the case of the arms 25 and 26. In the case of the arms 25 and 26 indicating two one dollars, it is understood that this arrangement applies when it is desired to indicate silver dollars. If it is 55 desired, on this machine, to indicate paper money, where there is a denomination of \$2.00, one of the projections, such as the projection 114, would be bent out of alignment with the corresponding indicator operating arm 41 so that an indication on that

indicator would mean one two dollar bill as distinguished from two silver dollars.

The operation of my machine is as follows: Current is first turned on by switch 137 and the motor is started. The dials ordinarily rest at the zero position, which position is indicated on the drawings, Fig. 3. After the dials have been set to the desired position, such as that shown in Fig. 3, by the handles 138 and 139 the button 81 is 75 pressed. This raises the contact block 79, closing the circuits through the magnets 130, 129, 128, 127, 124 on the dollar dial and magnets 123, 122 and 51 on the cents dial. These magnets draw up their armatures, 80 each one forcing its respective dog 50 in behind the shoulder 49 on the corresponding arms 32, 38, 39, 40, 43, 44, 45 and 46. Immediately after the contacts have been closed and the dogs placed in position in response 85 to the magnets energized by the closing of the selected contacts, the collar 103 is released by the arm 107 moving out beyond the end of pin 106 and the spring 105 moves this collar so that the shaft 15 is operatively 90 connected with the worm wheel 99 which is operated by the motor. As the shaft 15 revolves, the various arms 16 to 31 engage the respective indicator operating arms 32 to 47. Those arms in which the dog 50 has 95 been placed in position by the energization of the corresponding magnet when moved by the corresponding arm on the shaft 15 will move the corresponding indicator one or two steps dependent upon whether 100 the arms 16 to 31 are single or double arms. In all cases where the magnets have not been energized the corresponding arms 32 to 47 will be moved, but the indicator will not be operated as the dog 50 in those cases 105 has not been moved into position. When the shaft 15 has made a complete revolution, the arm 132 engages an arm 133 rigidly mounted on the shaft 55 on which all of the dogs 54 are mounted, thereby rocking 110 the shaft 55 so that the pins 136 engage the side of the grooves 135 thereby releasing these dogs from the push-arms of the electro-magnets, thereby permitting the dogs 50 to fall out of engagement with the indicator 115 arms, thereby operatively disconnecting all of the indicator operating arms. As the shaft 15 approaches the end of its revolution, the pin 106 on the collar 103 engages with the cam surface 109 on the end of the 120 member 107 and throws the collar to the left, as shown in Fig. 8, thereby disconnecting the shaft 15 from the worm wheel 99 and stopping the machine, whereby the shaft 15 is permitted to stop.

If, after setting up the dial and pressing the button 81 down so as to energize any of the magnets, it is discovered that the wrong figures have been set up on the dials, the mistake may be easily corrected by op- 130

erating the handle 134 fastened on to the end of the shaft 55. This acts to throw out the dogs 54 on the push arms, thereby permitting the dogs 50 to fall out of contact 5 with the arms 32 to 47, the same acting in the same manner as the trip 132 and 133. After the preceding operation has taken place, the indicators will show three twenty dollars; one ten dollar; one five dollar and 10 one one dollar; 1 fifty-cent piece; 1 twenty-five cent piece and one penny. If the dials are set so that the position A in the dollar dial is horizontal at the right of the center of the wheel, and the position A on the cents dial is in horizontal position at the left of the center of the wheel, the value represented would be \$38.93. If after these dials are thus set up the button 81 is pressed, the solenoids 129, 128, 127, 126 and 124 of the 20 dollar dial and the solenoids 123, 122, 121, 119, 118 and 51 of the cents dial will be energized. The mechanical operation here is identical with that already explained and need not be repeated. After this operation 25 has been completed, the indicators will show the following numbers of the following denominations: Four twenty dollars; two ten dollars; two five dollars; one two dollar; two one dollars; two fifty-cent pieces; two 30 twenty-five cent pieces; one ten-cent piece; one five cent piece and four pennies, making a total in dollars and cents of \$115.69, equal to \$76.76 plus \$38.93.

Having described my invention, what I 35 claim as new and desire to secure by Letters Patent is:

1. In a machine of the character described, the combination of a plurality of indicators, a plurality of indicator operating arms normally ineffective to operate said indicators, means for operatively connecting said arms to said indicators, magnets for selectively operating said means and means for simultaneously disconnecting all 45 of said arms from said indicators.

2. In a machine of the character described, the combination of a plurality of indicators, a shaft, a plurality of arms loosely mounted on said shaft normally ineffective to operate said indicators, means for operatively connecting said arms to said indicators, magnets for selectively operating said means whereby said indicators are selectively operated and means for simultaneously disconnecting all of said arms from 50 said indicators.

3. In a machine of the character described, the combination of a plurality of indicators representing different money values, means for selectively operating a plurality of said indicators, whereby after selective operation has taken place a number of times the total number of money units of each denomination will be represented on 60 one indicator and means for simultaneously

disconnecting all of said arms from said indicators.

4. In a machine of the character described, the combination of a shaft, a plurality of indicators mounted on said shaft, 70 a plurality of arms mounted on said shaft and adapted to operate about said shaft as an axis and normally disconnected from said indicators, a rotatable shaft, a plurality of arms on said rotatable shaft, one at least of 75 said arms arranged to engage one of each of the arms on said first shaft, means for operatively connecting said first arms to said indicators and means for operating said rotatable shaft. 80

5. In a machine of the character described, the combination of a plurality of indicators representing different money values, arms normally disconnected from said indicators and adapted to move concentrically with the wheels of said indicators, means for connecting said arms to said indicators, magnets for operating said means, means indicating money values corresponding to the values represented by said indicators for energizing said magnets and means for operating all of said arms during each operation of said machine. 90

6. In a machine of the character described, the combination of a shaft, a plurality of indicators mounted thereon, an arm for each indicator loosely mounted on said shaft and movable concentrically with said indicator, a dog pivoted eccentrically of said shaft for operatively connecting each arm 95 with its indicator and means for causing said dogs to operate to connect said arms to said indicators. 100

7. In a machine of the character described, the combination of a shaft, a plurality of indicators mounted thereon, an arm for each indicator loosely mounted on said shaft and movable concentrically with said indicator, a dog for operatively connecting each arm with its indicator, means 105 for causing said dogs to operate to connect said arms to said indicators, means for holding said dogs in operative position for a predetermined time, and means for releasing all of said holding means simultaneously. 110

8. In a machine of the character described, the combination of a shaft, a plurality of indicators mounted thereon, an arm for each indicator loosely mounted on said shaft, a dog for operatively connecting each 115 arm with its indicator, means for causing said dogs to operate to connect said arms to said indicators and means for holding said arms in operative position for a predetermined time and means for disengaging 120 said dogs before said indicators have been operated.

9. In a machine of the character described, the combination of a shaft, a plurality of indicators, a plurality of arms 130

loosely mounted on said shaft, a second shaft, a plurality of arms on said second shaft, one at least of said arms arranged to engage one of the first set of arms on said first shaft, means for operatively connecting said first arms to said indicators, a motor for operating said second shaft and means operated simultaneously with the means for connecting said first arms to the indicators for operatively connecting the motor to the second shaft.

10. In a machine of the character described, the combination of a shaft, a plurality of indicators, a plurality of arms mounted on said shaft, a second shaft, a plurality of arms on said second shaft, one at least of said arms arranged to engage one of the first set of arms on said first shaft, means for operatively connecting said first arms to said indicators, means for operating said second shaft, means operated simultaneously with the means for connecting said first arms to the indicators for operatively connecting the motor to the second shaft and for disconnecting said motor therefrom when said shaft has made substantially one revolution.

11. In a machine of the character described, the combination of a shaft, a plurality of indicators, a plurality of arms mounted on said shaft, a rotatable shaft, a plurality of arms on said rotatable shaft, one at least of said arms arranged to engage one of the first set of arms on said first shaft during each revolution of said second shaft, means for operatively connecting said first arms to said indicators, means for rotating said second shaft and means operated simultaneously with the means for connecting said first arms to the indicators for operatively connecting the motor to the second shaft and for disconnecting said motor from said shaft after the arms thereon have engaged the corresponding arms of the first set.

12. In a machine of the character described, the combination of a shaft, a plurality of indicators, a plurality of arms mounted on said shaft, a second shaft, a plurality of arms on said second shaft and rotatable therewith, one at least of said arms arranged to engage one of the first set of arms on said first shaft, dogs for operatively connecting said first arms to said indicators and means for operating said second shaft one revolution at a time.

13. In a machine of the character described, the combination of a shaft, a plurality of indicators, a plurality of arms mounted on said shaft, a second shaft, a plurality of arms on said second shaft and rotatable therewith, one at least of said arms arranged to engage one of each of the first set of arms on said first shaft during each revolution thereof, means for opera-

tively connecting said first arms to said indicators and means for operating said second shaft to cause the arms on said second shaft to engage the corresponding arms on the first shaft.

14. In a machine of the character described, the combination of a shaft, a plurality of indicators, a plurality of arms mounted on said shaft, a second shaft, a plurality of arms on said second shaft and rotatable therewith, one at least of said arms arranged to engage one of each of the first set of arms on said first shaft, dogs for operatively connecting said first arms to said indicators, means for operating said second shaft to cause the arms on said second shaft to engage the corresponding arms on the first shaft and means for stopping said second shaft.

15. In a machine of the character described, the combination of a shaft, a plurality of indicators, a plurality of arms normally loosely mounted on said shaft, a rotatable shaft, a plurality of arms rigidly mounted on said second shaft, one at least of said arms arranged to engage one of the arms on said first shaft, dogs for operatively connecting said first arms to said indicators, magnets for selectively operating said dogs and a motor for rotating said second shaft.

16. In a machine of the character described, the combination of a single indicator for each money denomination, a plurality of sets of movable contacts representing each money denomination, a magnet for each set of contacts and means whereby the magnets of a given denomination operate selectively on a single indicator to indicate the total number of denominational values represented by a plurality of selective operations.

17. In a machine of the character described, the combination of a dollar wheel and a cents wheel a plurality of sets of contacts on each of said wheels, some sets representing one and some more than one of different money denominations, an indicator for each denomination, a magnet for each set of contacts and means whereby the magnets controlled by the contacts representing the same denomination, whether one or more than one of that denomination, actuate the same indicator.

18. In a machine of the character described, the combination of a plurality of sets of rotatable contacts, a single magnet for each set of contacts, a movable contact for each magnet, means for placing certain selective combinations of the contacts of said sets of contacts in operative relation to said movable contacts, means for bringing said movable contacts into engagement with said selected contacts, whereby certain of said magnets are energized and record indicators operated by said magnets.

19. In a machine of the character de-

scribed, the combination of a shaft, a plurality of indicators, a plurality of arms for said indicators, a second shaft, a plurality of arms operated by said second shaft, one at least of said arms arranged to engage one of each of said first set of arms, means for operatively connecting said first arms to said indicators and means for operating said second shaft.

16 20. In a machine of the character described, the combination of a dollars wheel and a cents wheel each having a plurality of sets of contacts thereon, a plurality of magnets, a second set of contacts, one for each 15 of said magnets and a common contact, means for moving said dials to bring a desired combination of contacts thereon in

operative relation to said second set of contacts, means for moving the magnet contacts into engagement with the selected set of contacts, a plurality of indicators, arms for operating said indicators, said arms normally operatively disconnected from said indicators, means operated by said magnets for operatively connecting said arms to said 25 indicators and maintaining operative relation for a predetermined time, automatic means for operating said indicator arms, and automatic means for operatively disengaging said arms from said indicators at the 30 end of the operation of said machine.

In testimony whereof, I have signed my name to this specification.

HENRY ROHWER.
